United States Patent Office

Des. 191,402
Patented Sept. 26, 1961

191,402

DICTATING MACHINE

Heinz Huebner, Furth, Bavaria, Germany, assignor to
Max Grundig, Furth, Bavaria, Germany

Filed Apr. 18, 1960, Ser. No. 60,238

Claims priority, application Canada Dec. 8, 1959

Term of patent 14 years

(Cl. D26—14)

Fig. 1.

Fig. 2.

Fig. 3.

Fig. 4.

FIGURE 1 is a perspective view showing the top, the front and one end of a dictating machine embodying my new design.

FIGURE 2 is an end elevational view of the machine as seen from the right of FIGURE 1.

FIGURE 3 is a plan view of the dictating machine shown in FIGURES 1 and 2, and

FIGURE 4 is a front elevational view of the dictating machine.

I claim:

The ornamental design for a dictating machine, as shown.
